BRACKET HOLDER FOR TOOTHBRUSH TUBE

Arthur J. Gygie, 16316 S. Wilton Place, Gardena, Calif.

Filed May 17, 1961, Ser. No. 65,208

Term of patent 7 years

(Cl. D4—3)

FIGURE 1 is a side elevational view of a bracket holder for toothbrush tube showing my new design;

FIGURE 2 is a front view of the same;

FIGURE 3 is a rear view thereof;

FIGURE 4 is a top plan view of the same;

FIGURE 5 is a bottom plan view of the same;

FIGURE 6 is a perspective view of the same;

FIGURE 7 is a perspective view of the same with the cap open;

FIGURE 8 is a side elevational view with the cap open; and

FIGURE 9 is a top plan view with the cap open.

I claim:

The ornamental design for a bracket holder for toothbrush tube, substantially as shown.
